UNITED STATES PATENT OFFICE

MANIOUS GARL, OF AKRON, OHIO; LENNIE GARL EXECUTRIX OF SAID MANIOUS GARL, DECEASED

PUNCH REGISTER FOR RECORDING ELECTRICALLY TRANSMITTED SIGNALS, ETC.

Application filed June 12, 1930. Serial No. 460,623.

It is an especial object of my invention to provide a mechanism which is certain in its operation, and is not liable, through any failure of mechanism, to fail to record the precise number transmitted from the particular call box operated. It is an object of my invention to provide in a device of this type, novel cam mechanism for positive operation of a perforator and to eliminate the use of springs for the purpose. It is also an object of my invention to prevent any possibility of the punch sticking in the paper, as it is positively withdrawn after each operation.

It is also an object of my invention to provide a positive feed for the strip of paper; to provide novel means for controlling the operation of the punch and to eliminate the necessity for frequent winding of the clock mechanism in the punch.

It is further an object of my invention to provide novel means for actuating, adjusting and controlling the operation of a device of this character, and to provide novel means for feeding the paper on which the punch operates to register the calls.

It is also an object of my invention to provide the novel combination and arrangement of parts disclosed in the accompanying drawings, in which,—

Figure 1 is a perspective view of the exterior of the machine with the strip of paper in operative position to be punched;

Fig. 2 is a top plan view of the register with the top panel of the casing removed;

Fig. 3 is a bottom plan view of the register;

Fig. 4 is an end elevation viewed from the punch end of the machine with the end plate of the casing removed;

Fig. 5 is a detail vertical section through a portion of the register;

Fig. 6 is a longitudinal vertical section through the entire register, on line 6—6 of Fig. 2;

Fig. 7 is a detail vertical section through the casing containing the cam mechanism and punch, on line 7—7 of Fig. 2;

Fig. 8 is a section on line 8—8 of Fig. 7, at right angle to the plan on which Fig. 7 is taken;

Fig. 9 is also a section on line 8—8 of Fig.

7 showing a similar view of the cam mechanism to that shown in Fig. 8 but with the punch depressed;

Fig. 10 is a detail perspective view of the cam device removed from its casing;

Fig. 11 is a similar view to Fig. 10 but with the cam device in reversed position;

Fig. 12 is a detail section through the paper reel;

Fig. 13 is a section on line 13—13 of Fig. 12; and

Fig. 14 is a detail perspective view of members 36, 42, 38, 39, 45 and 35 as viewed from beneath those members.

Like characters of reference designate like parts in each of the several views.

Referring to the accompanying drawings, I provide a suitable metal base 1, having a suitable casing 2 mounted on same for carrying a paper reel 3 on which a roll of paper 4 is mounted.

The paper reel comprises the reel sides 3c rigidly affixed to the reel hubs 3b, the outer surface of which hubs are tapered inwardly in slightly conical shape, as illustrated in Fig. 12, to cause the wooden ring or hub 3a of the roll of paper to keep in a central position while in operation between the reel sides 3a. I further provide a suitable thumb nut 3d, as shown in Fig. 1, for fastening the reel sides in their normal spaced relation and also to permit of conveniently removing one side of the reel to place a new roll of paper 4 on the reel whenever required.

I provide a cam casing 5 attached to the main casing and having a slot 6 through which the strip of paper 4 is fed, the paper then passing between the lower or fixed roller 7 and the upper or movable paper feed roller 8.

Roller 8 is mounted on a pivoted arm 9. Arm 9 is mounted on a shaft 11 and is pressed towards roller 7 by a suitable enclosed (and preferably flat) spring 10, as shown in Figs. 1 and 2, whereby the rollers 8 and 7 engage the strip of paper 4. It is to be especially noted that the rollers 7 and 8 are so positioned relative to the slots 6 in the cam casing 5 through which the strip of paper 4 is fed as to engage the strip of paper in a plane offset 100

from its center so that the punch portion of the paper will not be engaged by the roller and danger of tearing the strip will thus be avoided.

5 Mounted in the cam casing 5 is a cam operated device 12, in the bottom of which the punch 13 is mounted. The cam operated element is provided with the two cam slots 14 and 15 in which the outer cam 16 and inner cam 17, respectively, travel. These cams function to positively drive the cam operated device and punch 13 in their respective downward and upward movements.

10 The cam slot or recess 14 has a diagonal or slanting surface 14b as its top or roof and an opening 14a as its bottom portion, while the cam slot or recess 15 is of like shape but exactly reversed with the slanting or diagonal surface 15b arranged on its bottom portion and its opening 15a arranged at the top. The punch 13 is rigidly affixed to the cam device and is preferably provided with an inwardly curved or broadly U-shaped bottom surface. This affords an easy punching of 15 the paper. While the punch illustrated in the drawing is designed for making a circular or disc punching, I may provide a punch member 13 of any desired shape, such as a diamond or a triangular shape if desired. 20 The cam device 12 is vertically movable in a suitable cam guide 5c to which the cam casing is detachably fastened, as shown in Fig. 7. I provide a suitable bottom strip 5a having a suitable shaped opening 5b for the punch to travel in when it descends past the slot 6 through which the strip of paper 4 is fed.

25 I provide an elliptical cam 16 traveling in the cam slot or recess 15 and a similar elliptical cam 17 disposed in a plane transversely of the cam 16 and traveling in the cam slot or recess 14. The cam 16 functions to positively drive the cam device and punch downwardly while the cam 17 functions to positively drive the punch and cam device upwardly. It will be particularly noted that the provision of this cam device eliminates any need or dependence on springs which have been found unsuitable and undesirable 30 for operating a punch mechanism of this kind where infallibility of operation is essential. The cams 16 and 17 are both affixed to the main shaft 18. Shaft 18 carries a gear pinion 19, as shown in Fig. 7, which pinion meshes with a train of gears 20a driven by a suitable double clock spring mechanism 20, as illustrated in Fig. 2. A conventional train of gears is utilized.

35 Main shaft 18 also carries a stopping arm 21 which is provided with heavy laterally projecting stops 22 approximately triangular in cross section and each of which have a slightly S-shaped tapered surface, as illustrated in Figs. 5 and 6. The reason for this tapered surface of the projecting stops is to

receive the impact of the rotating movement of the arm against the stop pin 23.

40 I also provide secondary smaller releasing pins 25 spaced from the lateral stops 22 and functioning to take up the impact of the rotary movement of the device to positively stop same at the appropriate time. After striking this stop pin 23 which is provided on the pivoted depending link or arm 24, as shown in Figs. 5 and 6, the tapered surface 45 of the projection stops 22 allow them to slide off from the stop pin 23 and allows the secondary smaller releasing pins 25 to contact with the pin 23 of the pivoted locking and releasing arm or link 24. This obviates danger of breaking off the lighter stop pins 37 and insures the positive operation of the device after each half rotation of the stopping arm and shaft 18.

50 As shown in Fig. 5, I provide a transverse shaft 26 in the upper portion of the casing, having a depending arm 24 which carries a lateral pin 23 which alternately engages with one of the pins 25 and is subsequently disengaged from same with each half rotation of 55 the stopping arm 21. The arm 24 is pivotally connected at 28 with the magnet operated arm 29 which latter arm is mounted on a transverse shaft 30. This arm 29 carries an armature plate 31 which is positioned to be 60 actuated when current is passed through the electro-magnets 32. I provide an adjustment screw 31a for armature 31.

65 As shown in Fig. 3, in connection with the electrical conductors leading to one of these 100 magnets, I may provide the approximately U-shaped clasps 33 to releasably receive a removable and conveniently replaceable fuse 34.

70 I provide a transverse shaft 35 near the end of the main casing to which the weight rod 105 36 is affixed. This weight rod is of sufficient length to extend to a position parallel with the stopping arm 21 and to be slidably engaged by the lateral pins 37 on that arm, these pins functioning to keep the weight rod continuously raised during the rotation of the 110 stopping arm.

75 Referring to Figs. 2 and 4 of the drawings, I provide an arm 38 pivotally mounted on shaft 35 and capable of lateral movement. As shown in Fig. 14 I provide a knife-blade 115 39 forming an extension of arm 38 and adapted to seat on the threaded shaft 40. I also provide a suitable small spring 41 affixed to this arm 38 to cause it to swing laterally toward an adjustably mounted fixed stop 42 which stop also is carried by the shaft 35. As shown in Fig. 4, the threaded shaft 40 carries a small gear 43 which in turn is operatively connected with the train of gears 20b 120 which are actuated by the clock spring mechanism 20, as shown in Fig. 2. As shown in Fig. 4, the threaded shaft 40 carries a pin 44 which functions to stop further movement of the machine when the pin 44 is engaged by 125 130

the L-shaped stop 45 which is in fact an extension of arm 38. The L-shaped stop 45 and the knife element 39 are integral.

I may provide an encased (and preferably flat) spring 46 affixed to the outer end of the shaft 30 which carries the armature 31, as shown in Figs. 4 and 5. The encased spring 46 functions to cause a rapid operation of the device. The stop 42, as shown in Fig. 14, is 10 adjustably mounted on shaft 35 by means of a suitable screw adjustment 50 to permit of its being shifted laterally on the shaft to regulate the feed of the paper—that is, the length of the strip of paper that will be fed out after 15 the machine has stopped punching. The knife holding arm 38 is also laterally adjustable by means of a screw adjustment 51 on the shaft 35. The purpose of this adjustment is to cause the L-shaped end 45 to lock more or 20 less tightly as desired on the stop 44 projecting from the threaded shaft as shown in Figs. 2 and 4.

As shown in Fig. 6 I provide an escapement wheel 55 keyed on the threaded shaft 40 and operatively engaged by the escapement 25 52 mounted on a transverse shaft 52a to which the weight arm 53 is adjustably mounted, this weight arm carrying adjustable weight 54.

As shown in Fig. 2 I provide the pivotally 30 mounted pawl 56 notched at its free end and adapted to engage a pin 57 in the main shaft 18 to prevent back lash of that shaft.

As shown in Fig. 1 I provide a suitable cup 48 removably mounted in suitable spring arms 35 47 and positioned under the cam device casting 5 to receive the punchings from the paper strip 4.

As shown in Figs. 1 and 2 I provide a handle (or other suitable means) 61 for engaging 40 the clock spring shaft 60 to wind the spring of the clock spring mechanism 20 which actuates the two trains of gears 20b and 20a as indicated in Fig. 2.

The device is operated electrically by 45 pulses transmitted from various signal apparatus at distant points and which apparatus is electrically connected by suitable electrical conduits with the contact members 59 and 59a, which are shown in Fig. 2, and which in 50 turn are electrically connected with the magnets 32 which when magnetized by a current of electricity actuate the armature 31 and thus cause a pivotal movement of the pivoted arm 24 to disengage the stop pin 23 from the lateral pin 37 of the rotating stop arm 21 carried by the main shaft 18. This main shaft 18 is under constant tension by reason of its operative connection through pinion 19 and the train of gears 20a with the clock 60 spring mechanism 20 which is arranged for movement in the direction indicated by the arrow in Fig. 2. Upon release and rotation of the double stopping arm 21 the cams 16 and 17 carried by main shaft 18 are rotated which 65 in turn causes a positive up and down move-

ment of the cam device 12 and punch 13 carried by that cam device to punch holes in the strip of paper 4. This strip of paper is fed along by its frictional engagement between rollers 7 and 8, the roller 7 being 70 mounted on a shaft which is driven by the train of gears 20b from the clock spring mechanism 20, this clock spring mechanism functioning to drive both the main shaft and the feed roller and the stop mechanism control simultaneously. 75

In operation an important advantage is attained by providing the double stopping arm 21 in that one punch is made at each half rotation of the shaft 18 and in turn this has 80 the effect of making it possible to wind the clock mechanism only half as often as would be necessary if a complete rotation of the shaft 18 was required for each operation of the punch mechanism. 85

It will also be particularly noted that the stopping arm and projections are of relatively large size and of heavy material to permit of the use of a heavy clock spring mechanism 20 for actuating the device and the heavy weight and relatively large size of these parts prevents any danger of breakage with the relatively powerful clock mechanism used in my register. 90

In registers heretofore manufactured, arms having a similar function to this device have made one complete revolution and have been of relatively light material and of different shape from my device with the result that frequent breakage of these parts occurred, 100 with consequent extra expense for changing and renewing of broken parts. 95

While the main shaft 18 and double stopping arm 21 are rotating the two lateral pins 37 on double stopping arm 21 function to successively contact with weight rod 36 and elevate it and rotate shaft 35 to which rod 36 is affixed sufficiently to raise arm 38 and thereby disengage knife blade 39 from the screw threaded shaft 40. This operation results 105 in continuous feeding of the paper strip during the transmission of electrical signals. 110

When the transmission of electrical impulses has been completed and the signal call thereby transmitted has been registered by a corresponding number of holes punched in the strip of paper 4, the main shaft 18 is stopped by engagement of the double stopping arm 21 with the lateral stop 23 on the arm 24 which arm is operatively connected with the armature 31. The weight rod 36 thereupon descends to its normal lowered position thus rotating shaft 35 to which it is affixed to a sufficient extent to lower the arm 38 so that its knife blade extension 39 will engage in the threads of the screw threaded shaft 40 which will cause the arm 38 to travel laterally due to its operative engagement with the screw threaded shaft until the L-shaped end 45 engages with the stop pin 130

44 carried by screw threaded shaft 40, as shown in Figs. 4 and 2. The effect of this limited travel of the blade 39 and shaft 38 in engagement with the screw threaded shaft 39 is to permit a short strip of three or four inches of the paper strip 4 to be fed out beyond the rollers 7 and 8 so that the paper strip may be readily torn off by the person using it at the fire station, police station or other central office without danger of tearing into the portion of the strip in which the punched holes appear and which punched holes indicate the number of the signal thereby registered by the machine to correspond with the number of the signal box from which the desired signal was transmitted from some distant portion of the city.

10 The above description describes the operation of the register on a so-called "open circuit." On a so-called "closed circuit" its action is identical so far as the mechanical features are concerned, the difference being only that in open circuit operation the armature of the electro magnet is attracted to the 20 coils when energized, while in closed circuit operation the armature of the electro magnet is released when the circuit is broken, and attracted and held by the coils when the circuit is again completed.

25 30 What I claim is:

1. In a punch register for recording electrically transmitted signals, the combination of a shaft, a pair of elongated cams on the shaft said cams being disposed in a direction

35 transversely to each other, a cam device having oppositely arranged cam slots in which the aforesaid cams travel to cause a positive upward and downward movement of the cam device, and a punch carried by the cam device.

40 45 2. In a positively operated punch register for recording electrically transmitted signals, the combination of a mechanically driven shaft, a pair of elliptical cams on the shaft said cams being disposed in a direction trans-

50 versely to each other, a cam device having oppositely arranged cam slots in which the aforesaid cams travel to cause a positive upward and downward movement of the cam device, and a punch carried by the cam device.

55 55 3. In a punch register for recording electrically transmitted signals, the combination of a mechanically driven shaft, a pair of elliptical cams on the shaft said cams being disposed in a direction transversely to each

60 other, a cam device having oppositely arranged cam slots in which the aforesaid cams travel to cause a positive upward and downward movement of the cam device, each cam slot having a slanting surface and having

65 65 an opening opposite said slanting surface, and a punch carried by said cam device, substantially as shown.

70 75 4. In a punch register for recording signals, the combination of a main shaft, means operatively connected with the main shaft

for revolving same, a double stopping arm mounted on the main shaft, said double stopping arm having heavy lateral projections functioning as stop elements a punch, a cam operated device to which the punch is attached, a cam actuating the cam device on each half revolution thereof, said cam being mounted on the main shaft.

75 80 5. In a punch register for recording signals, the combination of a main shaft, means operatively connected with the main shaft for revolving same, a double stopping arm mounted on the main shaft, said double stopping arm having heavy lateral projections functioning as stop elements, and having lateral smaller projecting release-pins spaced a like distance from the first mentioned projections a punch, a cam operated device to which the punch is attached, a cam actuating the cam device on each half revolution thereof, said cam being mounted on the main shaft.

85 90 6. In a punch register for recording signals, the combination of a main shaft, means operatively connected with the main shaft for revolving same, a double stopping arm mounted on the main shaft, said double stopping arm having heavy lateral projections functioning as stop elements, a depending arm having a laterally projecting pin adapted to engage the projections of the double 95 stopping arm to stop same, and means operatively connecting the arm with the armature of an electro-magnet whereby the depending arm may be electrically operated.

100 105 7. In a punch register for recording signals, the combination of a main shaft, means operatively connected with the main shaft for revolving same, a double stopping arm mounted on the main shaft, said double stopping arm having heavy lateral projections functioning as stop elements, and having lateral smaller projecting stop pins spaced a like distance from the first mentioned projections, a depending arm having a laterally projecting pin adapted to engage the projections of the double stopping arm to stop same, and means operatively connecting the arm with the armature of an electro-magnet, whereby the depending arm may be electrically operated.

110 115 8. In a punch register, the combination of a threaded shaft, a gear on said shaft, clock mechanism with which said gear is operatively connected, a punch device, means for positively feeding a strip of paper through the punch device, means operatively connecting said paper feeding means with the threaded shaft, means operatively connected with the threaded shaft for positively stopping the paper feeding means after a predetermined number of rotations of the threaded shaft, a weight rod operatively attached to said means, a double stopping arm having laterally projecting pins adapted to contact with the weight rod when the double 120 125 130 135 140

- stopping arm is rotated, the rotation of the double stopping arm thereby functioning to elevate the weight rod sufficiently to prevent the stopping means for stopping the feeding 5 of the strip of paper from functioning, a main shaft on which the double stopping arm is mounted, and means for controlling the operation of the double stopping arm in accordance with signals transmitted to the 10 register, and a punch device operated by the main shaft.
9. In a punch register, the combination of a threaded shaft, a gear on said shaft, clock mechanism with which said gear is operatively connected, a punch device, means for positively feeding a strip of paper through the punch device, means operatively connecting said paper feeding means with the threaded shaft, 15 means operatively connected with the threaded shaft for positively stopping the paper feeding means after a predetermined number of rotations of the threaded shaft, a weight rod operatively attached to said means, a double stopping arm 20 having laterally projecting pins adapted to contact with the weight rod when the double stopping arm is rotated, the rotation of the double stopping arm thereby functioning to elevate the weight rod sufficiently to prevent 25 the stopping means for stopping the threaded shaft from functioning to stop the feeding of the strip of paper, a main shaft on which the double stopping arm is mounted, a punch device operated by the main shaft, a pivoted 30 depending arm having a lateral stop adapted to be moved into or out of engagement with the double stopping arm to stop the rotation of same, and an electro-magnet electrically connected with said double stop arm to electrically control same in accordance with 35 signals received from a distant station.
10. In a punch register, the combination of a threaded shaft, a gear on said shaft, clock mechanism with which said gear is operatively connected, a punch device, means for positively feeding a strip of paper through the punch device, means operatively connecting said paper feeding means with the threaded shaft, 40 means operatively connected with the threaded shaft for positively stopping the paper feeding means after a predetermined number of rotations of the threaded shaft, a weight rod operatively attached to said means, a stopping arm having laterally projecting pins adapted to contact with the weight rod when the stopping arm is rotated, the rotation of the stopping arm thereby functioning to elevate the weight rod sufficiently to prevent the stopping means for stopping the threaded shaft from functioning to stop the feeding of the strip of paper, a main shaft on which the stopping arm is mounted, a pivoted depending arm having a lateral stop adapted to be moved in- 45 to or out of engagement with the stopping

arm to stop the rotation of same, and an electro-magnet electrically connected with said stop arm to electrically control same in accordance with signals received from a distant 70 station.

11. In a punch register of the type described, the combination of a threaded shaft, a stop pin affixed to the threaded shaft, a gear on said shaft, clock mechanism with which said gear is operatively connected, a punch device, means for positively feeding a strip of paper through the punch device, and means operatively connecting said paper feeding means with the threaded shaft, a transverse shaft, a stop member adjustably mounted on the shaft, a spring operated laterally swingable arm adjustably mounted on the shaft and adapted to be swung into operative engagement with the stop member, said swingable arm being also operatively connected with the threaded shaft whereby to stop same when it is swung into contact with the first mentioned stop element.
